UNITED STATES PATENT OFFICE

2,531,272

VAPORIZING TYPE BLAST WHIRL OIL BURNER

John O. Herbetz, Salt Lake City, Utah

Application April 29, 1948, Serial No. 23,947

5 Claims. (Cl. 158—91)

1

This invention relates to oil burners of the type adapted to maintain a body of oil for surface vaporization and blast combustion, either with natural or forced draft.

A variety of burners of this type have heretofore been developed, but so far as I am aware, none embody the structural features which I have found to produce superior results in practice.

Among the objects of my invention are:

To produce an unobstructed side-blast, whirl flame by means of a very simple and inexpensive construction;

To produce a flame having superior whirl characteristics;

To provide an effective whirl-sweep of vaporizing air immediately above the surface of the body of oil and within the confines of the oil-containing vessel;

To utilize whirl-producing fins as spacer elements between the oil-containing vessel and a gap-defining cover in such a manner that the burner gap is unobstructed and vaporizing heat is concentrated above the surface of the oil;

To provide, at least in certain embodiments, for the shifting of the cover relative to the oil-containing vessel for changing the width of the burner gap and varying the volume of the flame at different locations along said burner gap;

To provide an improved oil burner of the type concerned.

Further objects and features of the invention will become apparent from the following detailed description of the specific constructions illustrated in the accompanying drawings.

In the drawings, which exemplify rather than limit the inventive concepts:

Fig. 1 represents a top plan view of one form of my improved oil burner adapted especially for furnaces and heaters, flames being indicated schematically;

Fig. 2, a side elevation;

Fig. 3, a vertical section taken on the line 3—3, Fig. 1, an air conduit having been added;

Fig. 4, a view similar to that of Fig. 1, but illustrating a somewhat different construction adapted especially for cook stoves;

Fig. 5, a side elevation;

Fig. 6, a longitudinal vertical section taken on the line 6—6, Fig. 4; and

Fig. 7, a transversal vertical section taken on the line 7—7, Fig. 4.

Referring now to the drawings: the embodiment of Figs. 1, 2 and 3 comprises an annular trough 10 adapted to contain a body of oil 11,

2

supplied in regulated quantity through the pipe 12 by any suitable means, such as a gravity flow tank (not shown). The body of oil 11 presents a broad vaporizing surface 11a.

3 The trough 10 has an outer wall 13 and an inner wall 14 of lesser height, the latter defining a central opening 15 which serves as a passage for the inflow of air to the burner. If desired, an air conduit 16, Fig. 3, may be fitted to the opening 15 to supply air from any suitable source by either natural or forced draft in well known manner.

It is preferred that the trough 10 be provided with three short legs 17 to furnish proper support within the fire pot of a furnace or other heater. Advantageously, the entire trough is a casting of suitable metal, such as iron, and it is desirable that one of the legs be provided with a passage 18, Fig. 3, into the outer end of which 10 the oil-supply pipe 12 is threaded, the inner end opening into the bottom of the trough.

Superimposed upon the annular trough 10 is a circular plate cover 19, which has a central conical deflector 20 depending into the air-supply opening 15 for directing air outwardly toward the oil-containing trough. The cover 19 is supported on the inner and lower rim of the trough, that is to say, on the top of the inner wall 14 of the trough, by means of a multitude of curved heat-radiating fins 21 which depend from the underside of the cover and extend substantially radially intermediate the deflector 20 and the cover's circumferential periphery. These fins 21, seating as they do on the inner wall 14 of the trough, determine a circular burner gap 22 between the cover and the outer wall 13 of the trough. It should be noted that this burner gap 22 is completely unobstructed, thereby affording free sweep for flames emerging from the burner. It should be noted, further, that the fins 21 extend well below the outer rim of the trough 10, and are in fact disposed for the most part within the trough, thereby causing air from the air-supply opening 15 to swirl within the trough above the body of oil 11 prior to discharge through the burner gap. This, coupled with the heat concentrating and radiating character of the fins, enhances the vaporizing action of the device as well as imparting a desirable whirling motion to flames emerging from the burner.

As illustrated, shorter fins 23 of less vertical depth advantageously alternate with the fins 21, and hang freely within the trough 10 immediately above the surface 11a of the body of oil. These

further enhance the vaporizing action of the device.

Advantageously, neither the long nor the short fins merge with the deflector 20, thereby leaving open entrances to the flow channels between fins, such flow channels themselves being substantially unobstructed lengthwise to provide for unimpeded flow therethrough.

While the circular form of burner above described is especially suitable for certain instances of use, the novel features of the invention may be incorporated in other forms. For example, the elongate form illustrated in Figs. 4, 5, 6 and 7 is especially suited for use in cook stoves. There, both the trough 30 and gap-defining cover 31 are of essentially rectangular configuration.

The trough 30 extends peripherally about an air-supply opening 32, which may or may not have connected therewith a supply conduit such as that illustrated at 16 in the prior figures.

As in the prior embodiment, the inner wall 33 of the trough 30 is of less height than the outer wall 34, and serves to seat heat-radiating fins depending from the underside of the cover 31. In this instance, only fins 35 at opposite ends of the cover are curved. They radiate from the semi-circular ends of an elongate deflector 36, and serve to effect a whirling action of air and flame at opposite ends of the burner in a manner similar to the embodiment previously described. As illustrated, all the fins 35 seat upon inner wall 33 of the trough and are disposed in major extent below the level of the outer peripheral wall of the trough.

Intermediate the length of the cover 31 are straight fins 37, which, as illustrated, merge into the body of the deflector 36, see Fig. 7. While these fins do not produce as effective a swirling action of the air above the body of oil within the trough as do the fins 35, they do direct the flow in definite paths within the confines of the trough as defined by the wall 34, and render effective aid to surface vaporization of the body of oil. Both the fins 35 and the fins 37 by their seating on inner wall 33 of the trough determine the extent of the burner gap 38.

In this embodiment, because of the equal depths of the fins, the cover 31 may be shifted forwardly or backwardly or from side to side to vary the character of the burner gap and thereby control the volume of flame at any given location along the length of such gap, this being particularly advantageous for cook stoves.

The oil-containing portion of the trough 30 is preferably divided into three zones by the low partitions 39 and 40, Fig. 6, and 41, Fig. 7, the zones being individually supplied with oil through respective supply lines 42, see Fig. 5. This tends to stabilize burner action.

Whereas this invention is here illustrated and described with respect to preferred specific embodiments thereof, it should be understood that various changes may be made within the scope of the following claims.

What is claimed is:

1. An oil burner, comprising a trough surrounding and defining an air-supply opening, said trough having its outer wall of greater height than its inner wall and being adapted to contain a body of oil with a broad vaporizing surface; a cover for said trough and air-supply opening, said cover having a deflector depending substantially centrally from its underside into said opening for directing air outwardly toward said

trough; a multitude of heat-radiating fins depending from the underside of said cover in substantially radial arrangement between said deflector and the rim of said cover and defining a plurality of laterally-directed and substantially unobstructed flow channels, at least part of said multitude of fins seating upon the inner wall of the trough to support said cover and to determine a laterally-directed, peripheral burner gap between the peripheral margin of said cover and the outer wall of the trough, said fins having the major portion of their vertical depths depending into said trough below the rim of the outer wall thereof, so that said flow-channels are disposed to a major extent within the trough and below the said rim of the outer wall thereof, terminating within the trough and having their discharge openings directed laterally toward said burner gap below the overhanging peripheral margin of said cover.

2. An oil burner, comprising an annular trough for containing a body of oil with a broad vaporizing surface, the outer wall of said trough being of greater height than the inner wall which defines an air-supply opening; a circular cover for said trough and air-supply opening, said cover having a deflector depending centrally from its underside into the said opening for directing air outwardly toward the trough; a multitude of curved, heat-radiating fins depending from the underside of said cover and arranged radially between the said deflector and the rim of the cover, and defining a plurality of laterally-directed and substantially unobstructed flow channels, said fins being alternately long and short, the long fins having greater depth than the short fins and being arranged to seat upon the said inner wall of the trough to support the cover and to determine a laterally-directed peripheral burner gap between the peripheral margin of said cover and the outer wall of the trough and the short fins hanging freely within the trough, said fins having the major portion of their vertical depths depending into said trough below the rim of the outer wall thereof, so that said flow-channels are disposed to a major extent within the trough and below the said rim of the outer wall thereof, terminating within the trough and having their discharge openings directed laterally toward said burner gap below the overhanging peripheral margin of said cover.

3. An oil burner, comprising a trough rectangularly surrounding and defining an air-supply opening, said trough having its outer wall of greater height than its inner wall and being adapted to contain a body of oil with a broad vaporizing surface; a substantially rectangular cover for said trough and air-supply opening, said cover having an elongate deflector depending substantially centrally from its underside into said opening for directing air outwardly toward said trough; a multitude of heat-radiating fins depending from the underside of said cover in substantially radial arrangement between said deflector and the rim of said cover and defining a plurality of laterally-directed and substantially unobstructed flow channels, said fins seating upon the inner wall of the trough to support said cover and to determine a laterally-directed, peripheral burner gap between the peripheral margin of said cover and the outer wall of the trough, said fins having the major portion of their vertical depths depending into said trough below the rim of the outer wall thereof, so that said flow-channels are disposed to a major extent within the trough and

below the said rim of the outer wall thereof, terminating within the trough and having their discharge openings directed laterally toward said burner gap below the overhanging peripheral margin of said cover.

4. An oil burner as defined in claim 3, wherein the fins of equal depth so the cover may be shifted to vary the character of the peripheral burner gap.

5. An oil burner as defined in claim 3, where-
in the fins at opposite ends of the cover are curved,
while the fins intermediate the said ends are
straight.
